UNITED STATES PATENT OFFICE

JAMES SIM, OF CATHCART, GLASGOW, SCOTLAND, ASSIGNOR TO G. & J. WEIR, LIMITED,
OF GLASGOW, SCOTLAND

CONDENSING PLANT OF STEAMSHIPS

Application filed May 29, 1930, Serial No. 457,286, and in Great Britain June 12, 1929.

Many steamships already provided with propelling machinery comprising reciprocating multiple-expansion engines and air pumps of the Edwards type are having their efficiency 5 improved by being provided with exhaust steam turbines arranged to receive the steam discharged from the low-pressure cylinder. In order to benefit by this turbine adjunct, it is usually necessary to improve the condensing 10 arrangements. The condenser is therefore enlarged or re-arranged or replaced, and improvements introduced with regard to abstracting the air from it.

The present invention is not concerned with 15 improvements in the condenser, but it is concerned with improvements for abstracting the air therefrom. It is usually desired to retain the Edwards air pump and, to enable this to be done, a "vacuum-augmenter" is introduced 20 which withdraws the air from the condenser and delivers it into the discharge pipe from the bottom of the condenser to the bottom of the air pump.

With this arrangement the engine is started 25 without the turbine and then, at some convenient time—it may be after the ship has left the harbour and got into its stride—the vacuum-augmenter, and thereafter the turbine, is switched in. (A flexible clutch may be employed for this purpose).

Now, trouble is experienced by the air pump losing its water and becoming dry and thus failing to perform its required duty. This occurs after the vacuum-augmenter has 35 been started. The trouble is thought to be due to the pressure of discharge from the vacuum-augmenter which forces the water back along the delivery pipe from the air pump to the condenser.

40 The object of the present invention is to overcome this trouble.

The present invention is applied to an arrangement of condensing plant comprising a condenser, a reciprocating air pump, and an 45 ejector vacuum-augmenter which discharges the air from the condenser and delivers it into the discharge pipe from the bottom of the condenser to the air pump. The invention will be defined in the annexed claims. An 50 essential feature of the invention is a sealing

chamber on the discharge pipe from the bottom of the condenser to the air pump. This sealing chamber contains air in its upper portion and water in its lower portion, that is, there is a well of water at the bottom of the 55 chamber. The discharge from the vacuum-augmenter is delivered into the water in this well and below the surface of the water. The condensate from the condenser is delivered into the top of the sealing chamber so as to 60 fall freely and loosely through the chamber into the well at the bottom.

The accompanying drawing illustrates the carrying of the invention into effect.

c is the condenser, *a* the air pump, *v* the 65 vacuum-augmenter, and *s* the sealing chamber. The condensate flows from the condenser through the pipe *d* and the passage *e* into the distribution chamber *f* situated above the sealing chamber. The top of the sealing 70 chamber separating it from the distribution chamber consists of a perforated plate *g*. *w* is the well at the bottom of the sealing chamber.

The vacuum-augmenter withdraws the air 75 with vapour from the condenser by way of the pipe *t*, and discharges it through the pipe *u* into the perforated pipe *z* which is submerged in the water in the well *w*. The air rises 80 through this water into the air space *m* in the upper portion of the sealing chamber. The condensate falls through the holes in the perforated plate *g* and enters the sealing chamber in the form of spray, falling through the air space *m* on to the surface of the water in the 85 well.

The steam from the vacuum-augmenter is largely condensed in passing through the water in the well and by the spray, and the air is cooled and much reduced in volume. Both 90 water and air pass from the sealing chamber to the air pump by way of the pipe *r*.

The invention has been described with reference to an air pump of the Edwards type. The invention might however be employed 95 with other reciprocating air pumps.

Having thus described my invention, what I claim as new and desire to secure by Letters Patent is:—

1. A condensing plant for steamship's pro- 100

propelling machinery comprising, in combination, a condenser, a reciprocating air pump, an ejector vacuum-augmenter for withdrawing the air from the said condenser, a discharge pipe from the bottom of the said condenser to the said air pump, said pipe including a sealing chamber, this sealing chamber being adapted to contain air in its upper portion and water in its lower portion, means whereby the said vacuum-augmenter discharges into the said water and below the surface thereof, and means whereby the condensate from the said condenser is caused to fall freely and loosely through the upper portion of the said sealing chamber into the bottom portion.

2. A condensing plant for steamship's propelling machinery comprising, in combination, a condenser, a reciprocating air pump, an ejector vacuum-augmenter for withdrawing the air from the said condenser, a discharge pipe from the bottom of the said condenser to the said air pump, said pipe including a sealing chamber, this sealing chamber being adapted to contain air in its upper portion and water in its lower portion, means whereby the said vacuum-augmenter discharges into the said water and below the surface thereof, and means whereby the condensate from the said condenser is delivered in the form of spray into the upper portion of the said sealing chamber.

3. A condensing plant for steamship's propelling machinery comprising, in combination, a condenser, a reciprocating air pump, an ejector vacuum-augmenter for withdrawing the air from the said condenser, a discharge pipe from the bottom of the said condenser to the said air pump, said pipe including a sealing chamber, this sealing chamber being adapted to contain air in its upper portion and water in its lower portion, means whereby the said vacuum-augmenter discharges into the said water and below the surface thereof, a distribution chamber situated on top of the said sealing chamber, a perforated partition forming the bottom of the said distribution chamber and the top of the said sealing chamber, and means whereby the condensate from the said condenser is delivered into the said distribution chamber.

4. A condensing plant for steamship's propelling machinery comprising, in combination, a condenser, a reciprocating air pump, an ejector vacuum-augmenter for withdrawing the air from the said condenser, a discharge pipe from the bottom of the said condenser to the said air pump, said pipe including a sealing chamber, this sealing chamber being adapted to contain air in its upper portion and water in its lower portion, a perforated pipe immersed in the said water, means whereby the said vacuum-augmenter discharges into the said pipe, and means whereby the condensate from the said

condenser is caused to fall freely and loosely through the upper portion of the said sealing chamber into the bottom portion.

5. A condensing plant for steamship's propelling machinery comprising, in combination, a condenser, a reciprocating air pump, an ejector vacuum-augmenter for withdrawing the air from the said condenser, a discharge pipe from the bottom of the said condenser to the said air pump, said pipe including a sealing chamber, this sealing chamber being adapted to contain air in its upper portion and water in its lower portion, a perforated pipe immersed in the said water, means whereby the said vacuum-augmenter discharges into the said pipe, and means whereby the condensate from the said condenser is delivered in the form of spray into the upper portion of the said sealing chamber.

6. A condensing plant for steamship's propelling machinery comprising, in combination, a condenser, a reciprocating air pump, an ejector vacuum-augmenter for withdrawing the air from the said condenser, a discharge pipe from the bottom of the said condenser to the said air pump, said pipe including a sealing chamber, this sealing chamber being adapted to contain air in its upper portion and water in its lower portion, a perforated pipe immersed in the said water, means whereby the said vacuum-augmenter discharges into the said pipe, a distribution chamber situated on top of the said sealing chamber, a perforated partition forming the bottom of the said distribution chamber and the top of the said sealing chamber, and means whereby the condensate from the said condenser is delivered into the said distribution chamber.

I hereby sign my name to this specification.

JAMES SIM.
